CLAIM

The ornamental design for an electronic device, as shown and described.

DESCRIPTION

FIG. 1 is a perspective view of an electronic device showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion encircled in FIG. 7; and,

FIG. 10 is an enlarged view of the portion encircled in FIG. 8.

The oblique shade lines in the figures illustrate transparency or translucency.

The dot-dash broken lines illustrate areas of enlargement.
